UNITED STATES PATENT OFFICE.

DANIEL HARKINS, OF HUDSON, MASSACHUSETTS, ASSIGNOR OF ONE-HALF
TO L. DEWART APSLEY AND JUDSON H. COFFIN, BOTH OF SAME PLACE.

MACHINE FOR MAKING FIGURED GOSSAMER RUBBER GOODS.

SPECIFICATION forming part of Letters Patent No. 378,247, dated February 21, 1889.

Application filed October 10, 1887. Serial No. 251,872. (No model.)

To all whom it may concern:

Be it known that I, DANIEL HARKINS, of Hudson, in the county of Middlesex and State of Massachusetts, have invented certain new and useful Improvements in Machines for Making Figured Gossamer Rubber Goods, of which the following, taken in connection with the accompanying drawings, is a specification.

My invention relates to machines for making figured gossamer rubber goods; and it consists in certain novel features of construction, arrangement, and combination of parts, which will be readily understood by reference to the description of the drawings, and to the claims to be hereinafter given, and in which my invention is particularly pointed out.

Figure 1 of the drawings is a plan of a machine embodying my invention. Fig. 2 is a vertical section on line $\alpha\alpha$ on Fig. 1. Fig. 3 is a sectional plan of a portion of the machine, the cutting-plane being on line yy on Fig. 2, with the perforated pattern-belt removed. Fig. 4 is a partial vertical section through one of the side frames on line zz on Fig. 1, and illustrating the mechanism for adjusting the tension of the pattern-belt.

In the drawings, A A are the side frames of the stationary section of the machine, said frames being connected together by suitable tie-girts, as shown, and having mounted in bearings thereon the rolls B and C, the former being provided with the crank D, by which it may be revolved; or it may be provided with a pulley, by means of which and a belt leading from a main or counter shaft it may be automatically revolved.

E E represent the frame of another section of the machine arranged to be adjustable toward and from the frames A A in any well-known manner, and having mounted in bearings thereon the roll F, as shown. This frame E is placed at a variable distance from the frame A A, according to the length of the piece of fabric to be coated with rubber, said piece of fabric having its two ends cemented together to form an endless band, G, which is mounted upon the rolls B and F, as shown in Figs. 1 and 2.

The frames A have fitted thereto, so as to be adjustable in the direction of the length of the

machine, a pair of housings, H H, in suitable bearings in which are mounted the pressure-rolls I and I', between which the upper portion of the endless band of material G passes as it is fed through the machine. The frames A 55 are also provided with the upwardly-projecting arms A' A', in the upper ends of which are mounted one or more rolls, J, as shown in Figs. 1 and 2.

K is an endless band of thin flexible sheet to metal, as brass or copper, having cut through the same any desired figure which it may be desired to place upon the rubber-coated goods, said endless band passing between the pressure-rolls I and I' with the band of fabric G, into 65 close contact with which it is pressed between said rolls I and I' and the roll B; thence it passes under and partially around the roll C and over the roll or rolls J, as shown in Fig. 2.

The housings H H, carrying the rolls I I', 70 are adjusted to strain or tighten the band K by means of the shaft L, provided with the crank M, the grooved drums or wheels N N, carried by said shaft, the cords or chains O, connecting said housings and drums or wheels and adapted 75 to be wound upon the grooved portions of said wheels, said shaft being prevented from being turned backward by the engagement of the pawl P with the ratchet-wheel P', all as shown in Figs. 1 and 4.

R is a doctor-plate adjustably secured by the screws S to the frames A A, and provided with the guard-flanges R', extending therefrom toward the rolls I I', and resting at their lower edges upon the fabric G or the sheet-metal band K, near their outer edges, as shown in Fig. 3.

The operation of coating a piece of fabric with rubber and imprinting or coloring a series of figures of any desired design thereon 90 is as follows: The rolls I', C, and J, with the band K, being removed from the machine, and the doctor-plate R being in position with its lower edge pressing upon the endless band of fabric G, which has been placed upon the rolls 95 B and F, a quantity of the semi-liquid or paste-like rubber is placed upon said fabric contiguous to said doctor-plate and between the flanges R', and the roll B is revolved until the fabric G has passed beneath the doctor-plate a suf- 100

ficient number of times to coat said material with the desired thickness of rubber. The doctor-plate R is then removed and the rolls C, I', and J are placed in position with the band K thereon, the doctor-plate is replaced, with its lower edge pressing upon the upper surface of the lower portion of the perforated band K, and a proper quantity of semi-liquid prepared rubber of a different color to that first placed upon the fabric is placed contiguous to said doctor-plate and between its flanges, when the roll B is again revolved until the entire surface of the endless belt of fabric G has passed beneath said doctor-plate, the perforated band K moving in exact unison with said fabric and allowing a quantity of the coloring-matter to reach said fabric through each of the openings in said band K.

What I claim as new, and desire to secure by Letters Patent of the United States, is—

1. In a machine for making figured gossamer rubber goods, the combination, with a pair of rolls constructed and arranged to support, strain taut, and feed an endless band of fabric to be coated, of an endless band having a series of perforations cut through the same and arranged to move in contact and in unison with the fabric to be coated, and a doctor-plate constructed and arranged to press upon said

perforated band, and provided with guard-flanges near each end thereof, substantially as described.

2. The combination of the rolls B, C, F, I, I', and J, the perforated endless band K, the doctor-plate R, provided with the guard-flanges R', and means, substantially as described, for adjusting the roll I' to strain said perforated band taut, substantially as set forth.

3. In a machine for making figured gossamer rubber goods, the combination, with a pair of rolls constructed and arranged to support and feed an endless band of fabric to be coated, of an endless band having a series of figures or designs cut through the same, a series of rolls, as C, I, and J, for supporting said band and causing it to move in contact and in unison with said endless band of material, and a doctor-plate, R, constructed and arranged to operate substantially as and for the purpose described.

In testimony whereof I have signed my name to this specification, in the presence of two subscribing witnesses, on this 8th day of October, A. D. 1887.

DANIEL HARKINS.
